HEAT INSULATION CURTAIN

Elbert R. Sitton, Houston, Tex.

Application January 28, 1938, Serial No. 187,375

4 Claims. (Cl. 154—44)

The invention relates to supports for heat insulating material where the same is used upon the outer surfaces of heated containers.

In the insulating of hot upright containers or vessels such as fractionating towers, stabilizers, reaction chambers and the like, various types of heat insulating materials are employed. Among these are felted rolls or blankets of heat resisting fibers, such as mineral wool, rock wool, slag wool, lead wool, and the like, is quilted between layers of metal fabric or netting. These blankets of heat insulating materials are then applied to the exterior of the vessel or container to be insulated. The supports ordinarily employed merely furnish rests for the lower edges of the sheets of insulating material but in use the sheets of material sag and expose the surface of the container and are generally unsatisfactory after a comparatively short time.

It is an object of my invention to provide means for supporting insulating material either when in the form of sheets or when said material is in the form of blocks of various sizes.

I desire to provide a hanger of strong and somewhat flexible material, which is supported in spaced relation from the wall of the container, and thus allow the heat insulating materials to be placed beneath the same and attached firmly so that there is no opportunity for sagging or displacement of the materials from their original position.

The invention includes the placing of hangers along the outer surface of the container in relations spaced sufficiently close to satisfactorily support the particular insulating material which is employed.

It is a further object of the invention to provide supporting hangers of the character noted which may also serve as a support for an outer sheathing or weather coating placed outside of the insulating layer said hangers and said sheathing being so secured as to allow expansion of the insulated device.

The invention resides particularly in the construction and arrangement of the supports forming the subject of the invention and reference is made to the drawings herewith wherein the same is illustrated.

In the drawings,

Fig. 1 is a side view partly in elevation and partly in broken section illustrating the use of my insulation support.

Fig. 2 is a broken detail illustrating the use of my invention with insulating material arranged in blocks.

Fig. 3 is an enlarged sectional detail illustrating the manner of attachment of the materials to the supporting hangers.

Fig. 4 is a similar sectional detail taken on the plane 4—4 of Fig. 3.

Fig. 5 is a perspective view of one type of insulating unit which may be employed in connection with my invention.

Fig. 6 is a broken detail showing the use of another embodiment of my hanger.

Fig. 7 is a vertical section through the insulating device shown in Fig. 6.

I have shown my invention as employed upon a tower or container 1 of sheet metal constructed in the usual manner. To support the insulating material upon the outer surface of the tower I contemplate placing on the outer surface thereof horizontally aligned brackets 2 which are preferably of angle iron, the size of which is adjusted to the thickness of the layer of insulating material which is to be used. These brackets may be placed close together or, if desired, a hoop of angle iron may be attached to the outer surface of the tower, although ordinarily spaced brackets will be sufficient. These brackets are attached to the surface of the tower by welding or any other desired means and the horizontally extending web or support is formed with openings therein to receive bolts by means of which my supporting hangers are secured to the brackets.

The hangers which I prefer to use are made of straps of sheet metal of proper thickness to support the load of the insulating material. It is to be understood that the particular construction of these hangers may be varied both as to material and form without departing from the spirit of the invention. These straps shown at 3 in the different views are provided with openings at the upper end to receive bolts shown best at 4 in Fig. 3. These bolts extend through the horizontally disposed upper end of the strap and serve to form a rigid attachment between the bracket 2 and the hanger. The hanger extends downwardly from the outer edge of the bracket 4 and is provided with spaced openings 5 therein through which attaching wires or rings may extend.

The rows of brackets 2 are arranged circumferentially around the tower and are spaced apart vertically so as to form in effect a continuous hanger extending the full length of the tower, each hanger or strap being of sufficient length to accommodate the weight of the layer of material which it is to support.

The insulating material may be obtained in different forms. The ordinary form is a sheet or blanket of felted fibers of mineral wool and the like arranged between two sheets of woven wire 5 or screen. In Fig. 1 the size of these sheets is indicated at 6 and the hangers are spaced apart to accommodate the width of these sheets. I place the hanger in position and insert the edge of a sheet 6 underneath the hanger to project 10 beyond the same at one side, and the other side, indicated at 7, abuts against the edge of the next adjacent sheet. These sheets are then secured together by sewing a wire 8 along the seam provided between the two adjacent sheets. These 15 sheets are then secured to the hangers by loops of wire indicated at 9, which are extended through the thickness of the sheet of insulating material and then looped through one of the openings 5 in the hanger and tied or twisted so 20 as to form a firm attachment of the sheet of material to the hanger. As many of these loops 9 will be employed as are necessary to firmly support the adjacent sheet of insulating material. When the entire outer surface of the tower is 25 thus covered with insulating material firmly anchored in place, an outer weatherproof covering is then employed. This may be in the form of weatherproof cement of the desired heat-resisting qualities, but I have shown in Fig. 1 the use of a 30 sheet metal covering or sheath to entirely surround the outer surface of the insulating layer.

These sections of sheet metal are formed circumferentially around the tower and are supported in place each upper ring of sheeting overlapping the next lower adjacent one so that moisture and rain will be prevented from entering under the sheathing 18. Each particular layer of material will be secured in place by loops of wire 10, as shown in Fig. 1, said loops going 35 through openings in the upper margin of the sheathing ring or layer 18 and then strung thru an opening in the hanger. In this manner the hanger will support not only the insulating layer itself but also the outer sheath of weatherproofing material.

In Fig. 5 I have shown another form in which insulating material may be obtained. These blocks 11 are preferably provided with reinforcing wires or rods. There are longitudinal rods 50 12 at each side of the block and transverse wires or rods 13 engaging around the inner surface of the block and then bent around the side of the block sufficiently to secure it in position on the block. Grooves 14 may be formed in the edge of 55 the block to provide support for the cross wires or rods. Blocks thus formed may be placed in position on the outer surface of the tower and secured to the hangers as shown in Figs. 3 and 4. The cross wires 13 may be connected with the 60 hangers 3 by loops of wire 15. When thus placed at the outer surface of the tower and wired in position between the hanger and the outer surface of the tower they will be held firmly in position and will not be allowed to sag or move 65 away from the outer surface of the tower.

The hanger straps 3 to which these blocks are secured will be placed a distance apart normally about equal to the width of the block of insulating material. It will thus be possible to secure 70 the blocks in place in a manner similar to that disclosed relative to the sheets or blankets of insulating material.

Another form in which insulating material may come is in the shape of elongated bricks or blocks 75 of smaller dimension than that shown in Fig. 5.

These blocks may be built up around the outer surface of the tower or tank in the same manner as with the previously described insulating material. In securing these blocks in position hangers 3 are used as in the previous embodiments and wires or hoops of steel, shown at 16, 5 may be employed and such hoops will be spaced apart longitudinally of the container or tower so as to tie these blocks in position on the outer surface of the container. These hoops 16 which 10 are thus employed will be secured to the hanger 3 by loops of wire 15 similar to those shown in Fig. 3. This is disclosed in Fig. 2 and will be readily understood. However, these wire hoops 16 may be placed beneath the hanger, as shown 15 at the upper end of Fig. 2, or on the outside of the hanger, as shown at 16' in Fig. 2. As a further alternative, the wire forming the hoop may be threaded through openings 5 in the hangers as disclosed at 16" in Fig. 2.

With the use of my improved hanger therefore it will be possible to securely support the insulating material in position against the wall of the tower or container so that it may not sag or be displaced from its proper position on the outer surface of the container. Further, in all of the embodiments in which the insulating material may come it will be possible to furnish an outer weatherproofing cover either of metal sheeting or of cementitious material as is now common. 20 The structure of the hanger is simple. It is easily and quickly applied and furnishes a detachable connection between the insulating material and the container which allows removal or repair without a material loss of time in the 25 change. This hanger will, therefore, be superior to the usual means of attaching the insulating material in position and will also 30 cheapen the cost of insulation.

In the form of support shown in Figs. 6 and 7, 40 I contemplate forming a bracket 2' which may be secured to the outer surface of the tower 1 and project radially therefrom as in the previous embodiment. The heat insulating material 6 is secured in position, however, by a 45 different type of support. I have an outer layer of sheet metal 19 which is placed over the layer of insulating material, said sheet material having inwardly extending flanges or brackets 20 thereon which may engage above the brackets 2' and 50 be secured thereto by bolts 21.

The layer of sheet metal 19 depends downwardly in spaced relation to the wall of the tower and bears against the outer face of the insulating material. To secure the outer covering 19 firmly 55 in position so as to support the insulating material I extend, transversely of the insulating material, pins having heads 23 thereon to bear against the sheet metal 19. The inner ends are extended through the insulating material and 60 hooked into the inner wall of the woven wire on the insulating material and caught therein so as to hold the outer sheathing in position and connect the insulating material therewith.

In this form the inwardly extending bracket or 65 flange 20 upon this sheet metal covering may be cut out of the wall of the sheet metal as shown at 24 in Fig. 6, or manifestly it could be secured to the sheet metal by welding, riveting or other 70 similar means.

In this particular form the insulating covering may be secured to the sheet metal 19 before the assembled combination is hung in position. It 75 will be only necessary after the insulating bracket has been secured to the sheet metal to hang the

same upon the brackets 2' and to bolt it securely in position.

This form of my invention is particularly easy to assemble. It is simple and inexpensive and 5 forms a valuable feature of my invention.

What is claimed as new is:

1. A metal container for hot fluid, a plurality of circumferentially arranged brackets on the outer surface thereof, hangers depending vertically 10 downwardly from the outer sides of said brackets in positions spaced in parallel relation from the said outer surface, said hangers comprising flexible supporting members having openings therein to permit attachment thereto of insulating material, said hangers thus being free to move outwardly at their lower ends.

2. A metallic tower for heated fluid, supporting projections on the outer surface thereof, hanger straps depending from the outer ends of said projections, the lower ends of said straps hanging free in spaced relation to said tower, layers of heat insulating material between said straps and said tower and means to tie said heat insulating material to said hangers at spaced points along said 25 hangers.

3. Means for heat insulating a cylindrical upright heated surface comprising a plurality of horizontally arranged rows of brackets positioned circumferentially around said surface, metallic hangers depending from the outer ends of said 5 brackets, the lower ends of said hangers being free to move laterally, a layer of heat insulating material between said hangers and said surface, and means to secure said material to said hangers at spaced points along the length of said hangers. 10

4. An insulation for containers having a vertical wall, a bracket projecting therefrom, insulation hangers suspended from said bracket to hang along the vertical wall, the lower ends of said 15 hangers hanging free in spaced relation to said wall, said brackets and hangers providing a spacing between the inside of the hanger and said vertical wall of substantially the thickness of the insulation, and insulating material attached to 20 the inside of said hangers and thus suspended beneath said bracket so that there is no tendency for the insulation to sag.
